UNITED STATES PATENT OFFICE.

PHILIP A. SAVOY, OF FULLERTON, CALIFORNIA.

WASHING MACHINE.

Application filed January 6, 1925. Serial No. 747.

This invention relates to washing machines.

An object of this invention is to provide a washing machine in which a drum adapted to hold the clothes is rotatably mounted in a tank partially filled with water and constructed in such a manner that rotation of the drum will cause a circulation of water to pass in and out of the clothes and drum.

Another object of the invention is to provide an electric switch controlling a motor in connection with an operating mechanism adapted to stop the drum of the washing machine in a position that the door carried by the drum may be opened.

A further object is to provide a washing machine having a rotatable drum constructed in such a manner that the clothes therein will be turned over at each revolution of the drum.

These objects are attained by the disclosure herein set forth by the following description of the accompanying drawings, the novel features of the invention being pointed out in the appended claims.

Referring to the drawings:

Figure 1 is a front elevation of the washing machine, parts being broken away and shown in section;

Fig. 2 is a longitudinal section taken on the line 2—2 of Fig. 1;

Fig. 3 is a transverse section taken on the line 3—3 of Fig. 2;

Fig. 4 is a fragmentary section taken on the line 4—4 of Fig. 2;

Fig. 5 is an enlarged fragmentary front elevation showing an electric switch and opening mechanism;

Fig. 6 is a horizontal section taken on line 6—6 of Fig. 5;

Fig. 7 is a view analogous to Figure 6;

Fig. 8 is a vertical section taken on line 8—8 of Fig. 5; and

Fig. 9 is a section taken on line 9—9 of Fig. 5.

Referring to the accompanying drawings wherein similar reference characters designate similar parts throughout, 10 designates a base upon which is mounted a frame designated at 11 consisting of end plates 12 and 13 and side plates 14 and 15. The frame supports a tank, generally designated at 16. The tank has a curved bottom 17, vertical side walls 18 and 19 terminating in flanges

20 and 21, a front wall 22, and a rear wall 23 having flanges 24 and 25 respectively.

A bearing 26 is secured to the front wall 22 and has a bore 27, a counter bore 28, an externally threaded portion 29 and a gland 30 adapted to compress packing 31 in the counter bore 28. A bearing 32 is secured to the rear wall 23 and has an opening 33 between arms 34.

A drum 35 is axially mounted in the tank 16. The drum consists of flat end plates 36 and 37, semi-circular eccentric side walls 38 and 39 joined at their extremities by perforated offset plates 40 and 41. The side wall 38 has an opening 42 closed by a door 43 having a suitable latch 44 and a hinge 45. The side walls 38 and 39 and the door 43 have a series of longitudinal inwardly projecting ruffles 46 having apertures 47 therein. The offset plate 41 projects inwardly and forms a baffle 48. A spider frame 49 is secured to the front wall 36 and has a central hub 50, in which is formed a square opening 51 having tapered sides 52. A spider frame 53 is secured to the rear wall 37 and has a hub 54 in which is secured a spindle 55. The spindle 55 rests in the bearing 32, and the opening 51 in the hub 50 engages a square shank 56 having tapered faces 57 formed integral on a shaft 58 mounted in a bearing 26. A leaf spring 59 is secured to the bearing 32 and engages the spindle 55 in order to hold the hub 50 and the shank 56 tightly engaged. A beveled gear 60 is secured to the shaft 50 and meshes with a gear 61 secured to a shaft 62 carrying a worm wheel 63 meshing with a worm 64 secured to a horizontal shaft 65 connected to a shaft 66 of a motor 67 by a coupling 68.

The gears 60 and 61 are enclosed in a gear case 69 fastened to upright angle irons 70 between horizontal angle irons 71 secured to the front plate 22. A second worm wheel 72 meshes with the worm 64 and is secured to a vertical shaft 73 which may be used for operating a wringer (not shown). The worm 64 and the worm wheels 63 and 72 are enclosed in a housing, generally designated at 74. The housing 74 is made in two sections 75 and 76, the section 76 being secured to the base 10 and the section 75 connected to the section 76 by bolts 77. The sections 75 and 76 when secured together

form depending bearings 78 and 79 adapted to receive the ends of the shafts 62 and 73, and also carry bearings 80 and 81 for supporting the horizontal shaft 65. A sleeve 82 surrounds the shaft 62 and a sleeve 83 surrounds the shaft 73, and a cover 84 is fastened to the gear case 69, thereby enclosing all the transmission.

A removable cover 86 rests on the flanges 10 20, 21, 24 and 25 of the tank 16. The bottom 17 of the tank 16 is provided with a longitudinal channel 87 in registration with an aperture 88 in the front plate 22. Water in the tank may be drained by opening a 15 valve 89 secured to the front plate 22.

A switch, generally designated at 90, for controlling an electric circuit through the motor 67 is constructed as follows:

A box 91 formed of fiber, or other insulating material, is secured to the front plate 22 in which is pivotally mounted a bar 92 of conductive material adapted to engage a contact 93. A circuit being closed when the bar 92 engages the contact 93 through insulated 25 conductors 94 and 95 leading to the motor 67 and a suitable source of electric energy.

A handle 96 formed of insulating material, is secured to the bar 92, and a removable cover 97 is fastened to the switch box by 30 screws 98.

It is desirable that the drum 35 be stopped with the door 43 in a position that it may be opened as shown in Fig. 3, and is accomplished by a switch operating mechanism 35 generally designated at 99 constructed as follows:

One end of a shaft 100 is mounted in a bearing 101 secured to the front face of the gear case 69 and the other end extends 40 through a bushing 102 in the wall of the gear case.

The shaft carries a fixed crank 104 and a rocker arm 105 slidable on a square portion 106. A shift lever 107 having bifurcated 45 ends 108 engaging the rocker arm, is pivotally mounted on a pin 109 carried by brackets 110 secured to the top of the gear case. An expansion coil spring 111 surrounds the shaft and is interposed between the crank 50 104 and rocker arm 105.

A tappet 112 is secured to the inner face of the bevel gear 60 and a link 113 is pivotally connected to the crank and handle 96 of the bar 92.

55 The washing machine is started by manually closing the switch 90. When the switch is closed the parts constituting the switch operating mechanism will assume the position shown in Figs. 5, 6, 8 and 9, it being noted that the rocker arm 105 is out of 60 registration with the tappet 112.

When it is desired to stop the machine the shift lever is pulled forward and temporarily held in the position shown in dotted 65 lines in Fig. 8, the movement of which will

bring the rocker arm into the path traversed by the tappet. (See Fig. 7). As the drum rotates the tappet will engage and lift the rocker arm, thereby rocking the shaft and crank, which in turn will open the switch by 70 means of the link, as shown in Figure 1, thus break the circuit to the motor. The drum will stop rotating shortly after the circuit to the motor is cut off, and will stop in a position that the door may be opened 75 as the door and tappet are in fixed relative positions.

When it is desired to use the washing machine the cover 86 is removed and the door 43 opened. Water is poured into the drum 80 through the opening 42 and will seek a level in the tank through the apertures 47, the clothes to be washed are placed in the drum and the door 43 is closed and latched. When the washing machine is in operation the 85 drum rotates in the direction of the arrow A. (See Fig. 3). As the drum rotates the clothes therein will be raised in the water due to the action of the eccentric side walls and turned over by the riffle. The water in the 90 drum will seek a level thereby circulating in and out of the clothes.

From the construction it will be seen that the washing machine is comparatively simple in construction and is very effective in performing its intended functions, as there is a continual circulation of water through the clothes, the rotation of the drum causing a pumping action through the apertures 95 therein. 100

It is to be noted that in the operation of my washing machine as it rotates in the direction of the arrow A as shown in Fig. 3, when the perforated offset plates 40 and 41 pass through the water the water is injected 105 with considerable force through the apertures and also as the apertures 47 in the corrugations forming the riffles are on the apex of these corrugations the water will be projected radially inwardly from said apertures. At the same time the clothes are given a rolling and turning movement by the riffles and the projecting baffle 48 tends to lift the clothes above the level of the water in the 110 washing machine and drop the clothes to the lowest side of the rotating drum. Therefore 115 the clothes are not merely subjected to a turning action in the water but are also subjected to jets of water impinging on the clothes as above mentioned. 120

It will be understood that various changes in the detail of construction may be made without departing from the spirit or scope of the invention as defined by the appended claims. 125

I claim:

1. In a washing machine, a drum having flat end walls, curved side walls eccentrically mounted, formed of sheet metal having a series of corrugations therein forming riffles, 130

said corrugations projecting inwardly and having apertures on the apexes of the corrugations, radial perforated plates connecting the outer part of one wall section to the 5 inner part of an adjacent wall section, said radial plates having perforations there-through, a baffle formed at the connection of one of the radial plates and the connecting section by extending the plate inwardly beyond the 10 section and connecting the section inwardly with the inwardly projecting plate and having a door with longitudinal inwardly projecting ruffles hinged to one of the sections adjacent one of the offset plates, and means to mount the drum and rotate the 15 drum on its axis.

2. In a washing machine, a drum comprising flat end walls, semi-circular eccentric side walls, radial perforated plates connecting the extremities of said eccentric side walls, one of said perforated plates being extended inwardly beyond the side wall forming an inwardly projecting baffle.

In testimony whereof I have signed my name to this specification.

P. A. SAVOY.
